INVENTOR

John W. Stephenson

UNITED STATES PATENT OFFICE.

JOHN W. STEPHENSON, OF TOLEDO, OHIO, ASSIGNOR TO THE NATIONAL
MALLEABLE CASTINGS COMPANY, OF CLEVELAND, OHIO.

RAILWAY-TRACK APPLIANCE.

SPECIFICATION forming part of Letters Patent No. 681,820, dated September 3, 1901.

Application filed July 25, 1900. Serial No. 24,779. (No model.)

To all whom it may concern:

Be it known that I, JOHN W. STEPHENSON, of Toledo, in the county of Lucas and State of Ohio, have invented a new and useful Improvement in Railway-Track Appliances, of which the following is a full, clear, and exact description, reference being had to the accompanying drawings, forming part of this specification, in which—

10 Figure 1 shows in perspective view a section of a railway-track provided with my improved devices. Fig. 2 is a plan view of the rail-brace, and Fig. 3 is a vertical section on the line III III of Fig. 2.

15 In the drawings, 2 2' represent the rails of a railway-track. The rail 2', which on a curve is the outside rail, is fitted with a brace constructed as follows:

20 3 is a tie-plate having a longitudinal shoulder 4, against which the inner flange of the rail abuts, and having opposite thereto a shoulder 5, which is tapered or undercut, as shown, and constitutes an abutment against which the rear end of the brace 6 has a sliding bearing, and this shoulder is also inclined longitudinally relatively to the rail and to its companion shoulder 4, so that when the brace is forced along the same it will act as a wedge and will be forced against the head and flange

25 30 of the rail, coming to a firm bearing thereon. The brace 6 has a bearing on the under side of the head and the upper side of the flange of the rail. The plate 3 is held by spikes 7 or otherwise to the tie 8, and the brace is held

35 in position by a spike 9 or like device, which is driven into the tie through a hole in a flange of the brace 6 and through a slot 10 in the plate 3, the slot permitting the brace to be forced along its inclined shoulder to a

40 solid bearing against the rail to any extent required without preventing the driving of the spike 9. When the spikes are driven, the parts are held rigidly in position and the rail is braced with great security even when the

45 tie is of soft wood having feeble holding power on the spikes. On the other rail 2 there may be a brace like the one just described; but I preferably employ on it a tie-plate 11, on which the rail rests and which is held to the

50 rail by spikes 12 or the like. This plate is preferably connected with the plate 3 by a tie-rod 13, fitted in outwardly open sockets 14 on the under sides and inner margins of

the two plates and having holes which register with spike-holes 15, formed in the sockets. The parts having been assembled as shown in the drawings, spikes 16 or the like are driven through the registering holes into the tie, thus fastening the tie-rod to the plates, and by holding the plates together the tie-rod prevents the rails from spreading. This feature of my invention contributes greatly to the strength of the track. It is simple and cheap and is of practical value in railway construction.

65 Within the scope of my invention as defined in the claims changes may be made by the skilled mechanic. Thus the tie-rod 13 may be used with tie-plates of various forms—for example, with two tie-plates like the plate 70 3 or two tie-plates like the plate 11.

65 What I claim is—

1. The combination with a railroad-rail, of a rail-brace having a bearing against the upper side of the flange and the under side of the head of the rail, and a tie-plate on which the brace is set, said tie-plate having a longitudinally-inclined rear bearing for the rail-brace, said brace having a spike-hole, and the tie-plate having a slot registering therewith; substantially as described.

75 2. A tie-plate adapted to rest on the surface of a tie under a rail, and having on its under side and inner margin a socket for the reception of a tie-rod, said socket being open 85 at its end for the free insertion of a tie-rod; substantially as described.

3. The combination of the rails of a railway-track, tie-plates therefor, a tie-rod connecting the tie-plates and connected therewith by spikes passed vertically through the plates and tie-rod; substantially as described.

90 4. The combination with a railroad-rail, of a rail-brace, having a bearing against the upper side of the flange and the under side of the head of the rail, and a tie-plate on which the brace is set, said tie-plate having a longitudinally-inclined rear bearing for the rail-brace; substantially as described.

95 In testimony whereof I have hereunto set my hand.

JOHN W. STEPHENSON.
